UNITED STATES PATENT OFFICE

118,070

DESIGN FOR AN OIL BURNER

Joseph A. D'Elia, Bridgeport, Conn.

Application July 22, 1939, Serial No. 86,181

Term of patent 14 years

To all whom it may concern:

Be it known that I, Joseph A. D'Elia, a citizen of the United States, residing at Bridgeport, in the county of Fairfield and State of Connecticut, have invented a new, original, and ornamental Design for an Oil Burner, of which the following is a specification, reference being had to the accompanying drawing, forming part thereof.

Fig. 1 is a perspective view of the oil burner showing my new design, the view being taken looking from the rear and toward the right of the burner; and

Fig. 2 is another perspective view of my said oil burner but taken looking from the front and toward the right of the burner.

I claim:

The ornamental design for an oil burner, substantially as shown.

JOSEPH A. D'ELIA.
